UNITED STATES PATENT OFFICE.

ANTHONY SOREN BUSK, OF WOODHAVEN, NEW YORK, ASSIGNOR TO R. HOE AND CO., OF NEW YORK, N. Y., A CORPORATION OF NEW YORK.

PRINTING-MACHINE.

1,339,099.

Specification of Letters Patent.

Patented May 4, 1920.

Application filed August 11, 1917. Serial No. 185,677.

To all whom it may concern:

Be it known that I, ANTHONY S. BUSK, a citizen of the United States, residing at Woodhaven, county of Queens, and State of New York, have invented certain new and useful Improvements in Printing-Machines, fully described and represented in the following specification and the accompanying drawings, forming a part of the same.

10 This invention relates to certain improvements in printing machines, and particularly that class of printing machines where-in a sheet, after it has been printed, may be scored or cut and delivered from the machine, and the invention has for its especial object the provision of an improved mechanism for driving the scoring or cutting device so that it may coöperate with the printing mechanism to cut or score a sheet after 15 it has been printed, or, where such scoring or cutting is not desired, the cutting or scoring mechanism may be silenced without interrupting the operation of the printing mechanism, so that the latter may operate 20 in the usual manner.

Another object of the invention is to provide a driving mechanism of simple form for effecting the principal object of the invention, the mechanism of which is readily 25 accessible and easily controlled and operated.

With these and other objects in view, the invention consists in certain novel parts and combinations which will be described in 30 connection with the accompanying drawings, in which—

Figure 1 is a side elevation of a printing machine showing a cutting and scoring mechanism in operative relation therewith;

40 Fig. 2 is a plan view, partly in section and partly broken away, on the line 2—2 of Fig. 1; and

Fig. 3 is an end elevation, partly in section and partly broken away, of part of the machine shown in Fig. 1, Figs. 2 and 3 illustrating in detail and on an enlarged scale 45 the improved driving mechanism.

Referring now to these drawings in detail, the machine chosen to illustrate the invention is a sheet fed rotary machine in which the sheets are fed from a pile and in which the printing elements are cylinders adapted to print a plurality of colors on a sheet, but it will be understood that

the invention is applicable to other types 55 of machines in which sheets may be fed from other sources of supply than a pile and in which all the printing elements are not cylinders.

Referring to the particular machine illustrated the various mechanisms are supported in suitable frames 1, which may be of any usual or desired construction and configuration.

The particular machine shown is arranged to print four or less colors and to 65 cut or score the sheet during its travel through the machine. The forms, which may be of any suitable type, are carried by form cylinders 2, 3, 4 and 5, inked by the 70 usual inking mechanism and arranged to successively print on a sheet, these form cylinders being suitably mounted in the frames 1 before referred to. These form cylinders coöperate with an impression 75 member which, in the particular machine illustrated, is a large impression cylinder 6 provided with suitable sheet taking devices, such devices, in the present instance, being grippers 7, these grippers being operated in 80 the usual manner to take sheets which are fed thereto from a feed board 8, the impression cylinder and feed board being suitably mounted in the frames 1.

In machines constructed in accordance 85 with the invention, there will be provided a cutting or scoring mechanism by which the sheets, after printing, may be cut or scored prior to their delivery from the machine.

This cutting or scoring mechanism may 90 vary somewhat in construction, but will include a pair of coöperating members, one of which will carry the cutting or scoring devices, and the other of which will act as an abutment against which the cutting or 95 scoring is effected, and in machines embodying the invention in its best form, the cutting and scoring devices will include a form of the character required indicated by the numeral 9 (Fig. 1), this form being carried 100 on a support, as a bed 10, driven as herein-after referred to. Coöperating with the bed or other support and the cutting or scoring devices carried thereby, is a coöperating member acting as an abutment for effecting the cutting or scoring operation. The particular character of this member may vary. As in some instances it may be de-

sired to operate the machine as a straight printing machine, without the cutting or scoring devices operating, it will be found convenient to employ a part of the delivery mechanism to effect the function of this co-operating member. In the particular machine illustrated, therefore, a delivery cylinder 11, suitably mounted in the frame 1 of the machine is provided, this cylinder being provided with sheet taking devices, such as grippers 12 for holding the sheet thereon while it is cut or scored against the cutting or scoring form 9, the cylinder 11 thus acting as an abutment against which the cutting or scoring is effected. This delivery cylinder 11, whether the machine is used with a cutter or scorer in operation or not, may deliver the sheets from the machine to any suitable final delivery, as tapes 13.

The sheets are presented to this delivery cylinder from the printing elements in any suitable manner. In the particular construction illustrated, there is provided a transfer cylinder 14 provided with sheet taking devices, as grippers 15, which take the sheets when they are released by the grippers 7 of the impression cylinder and transfer them to the sheet taking devices 12 of the delivery cylinder 11. This construction is preferable, as the sheet is under positive gripper control during its passage through the machine.

In machines constructed in accordance with the invention, a driving mechanism is provided whereby the printing and delivery cylinders and the bed, when the scoring form support is a bed, may be driven from a single source of power, or the bed may be silenced without interrupting the printing and delivery mechanism, so that the press, if desired, can be operated without the cutter or scorer. The particular construction for effecting this may be somewhat varied, but in the particular construction illustrated there is provided a power shaft 16 suitably mounted in the framework of the machine, this shaft carrying at one end a pulley 17 driven by a belt 18 from a pulley 19 on the shaft of a motor, indicated generally by the numeral 20. The power shaft 16 has at one end a driving pinion 21, which is in mesh with a clutch gear 22 having a clutch face 22' mounted so as to be free to rotate on a short driven shaft 23 suitably journaled in the machine frame, sidewise movement of the gear being prevented by a collar 23'. Fast on the shaft 23 is a clutch member 24 which can be slid in and out of engagement with the clutch gear 22, as hereinafter referred to. The face of the clutch gear 22, opposite the clutch face 22', is formed with a hub or extension 25, to which is secured, so as to rotate therewith, as by a key 26, a gear 27, which gear is in mesh with an intermediate gear 28, which in turn meshes

with a gear 29 on the delivery cylinder 11, before referred to, this gear 29 meshing with a gear 30 on the transfer cylinder 14, which in turn meshes with a gear 31 on the impression cylinder 6, these cylinders being 70 thus driven.

The bed 10, on which is carried the cutting or creasing form 9, before referred to, is mounted to be reciprocated beneath the delivery cylinder 11 in suitable guides 32 rising from the bed of the machine. The reciprocation of the bed may be effected in any desired manner and through various constructions. In the particular construction illustrated this is effected by means of a rack 33 extending from a bracket 34 secured to the underside of the bed and mounted to slide in guide 35 secured to the frame of the machine. This rack is reciprocated in the particular construction shown by means of a spur gear 36 carried on one end of a shaft 37 pivotally connected at 38 through a coupling 39 to the inner end of the driven shaft 23, before referred to. When it is desired to operate the bed, the clutch member 24, which, as before stated, is mounted fast on the driven shaft 23, is thrown into engagement with the clutch member 22' of the clutch gear 22, thereby locking this gear to the shaft 23 and causing 95 the shaft 23 and the shaft 37 to rotate. The shaft 37 is, as before stated, pivotally mounted so as to permit the gear 36 to walk around the rack 33, the reversal of the bed being effected by the gear 36 dropping below 100 the rack on the return movement. A suitable guide, as 40, is provided secured to the frame of the machine, in which works a block 41 on the shaft 37. A stop 42, with which the block 41 contacts, is provided 105 for limiting the downward movement of the shaft and insuring the gear 36 being in mesh with the rack when it is dropped to the underside thereof. If desired, a bearer 43 may be provided, moving with the rack, 110 with which co-operates a flange 44 on the outer face of the gear 36, this bearer and flange taking the weight of the gear off the rack when the gear is in the upper position, as shown in Fig. 3.

It will be seen from the foregoing that a simple construction has been provided whereby a sheet fed press may be provided with a cutting or scoring mechanism which can be driven from the same source of 120 power as the printing elements of the machine, but which cutting or scoring mechanism may be silenced without interrupting or otherwise disarranging the operation of the printing elements of the machine, thus 125 effecting a very compact structure in which no adjustment other than the throwing of the clutch is necessary.

It will be understood that various changes may be made in the specific construction of 130

the mechanism employed for carrying out the invention, and that the invention is not to be restricted to the precise details of construction shown and described.

5. What I claim is: 1. In a printing machine, the combination of a printing couple, reciprocating sheet cutting or scoring devices for cutting or scoring the sheet after printing, means for driving the couple, connections from the printing couple driving mechanism for driving the cutting or scoring devices, and connections whereby the scoring or cutting devices may be silenced without interrupting 15 the operation of the printing couple driving mechanism.

2. In a printing machine, the combination of a printing couple, a movable support, sheet cutting and scoring devices carried thereby, a delivery mechanism to which the sheet is delivered from the printing couple coöperating with the bed to cut or score the sheet, means for driving the couple, means whereby the support is driven from the printing 20 couple driving mechanism, and connections for throwing the support out of operation without interrupting the operation of the printing couple driving mechanism.

3. In a printing machine, the combination of a printing couple, a movable bed, sheet cutting or scoring devices carried thereby, a delivery mechanism to which the sheet is delivered from the printing couple acting as an abutment against which the scoring 35 mechanism operates to score or cut the sheet after it is printed, means for driving the couple, means for driving the bed from the printing couple driving mechanism, and connections whereby the bed may be thrown 40 out of operation without interrupting the operation of the printing couple driving mechanism or the delivery mechanism.

4. In a printing machine, the combination of a printing couple, a movable bed, sheet cutting or scoring devices carried thereby, means for driving the couple, means for driving the bed from the printing couple driving mechanism, a delivery cylinder to which the sheets are delivered 45 from the printing couple which coöperates with the cutting and scoring devices carried by the bed for effecting a cutting and scoring of the sheet after printing, and connections whereby the bed may be thrown out 50 of operation without interrupting the operation of the printing couple driving mechanism.

5. In a printing machine, the combination of a printing couple, reciprocating sheet 55 cutting or scoring devices arranged to cut or score a sheet after it is printed, a common means for continuously driving the printing couple and operating the cutting or scoring devices, and means for rendering 60 the cutting or scoring devices inoperative.

6. In a printing machine, the combination of a printing couple, a reciprocating bed provided with cutting or scoring devices arranged to cut or score a sheet after printing, a common means for continuously driving the printing couple and for effecting reciprocation of the bed, and connections whereby the bed reciprocating mechanism may be rendered inoperative. 70

7. In a printing machine, the combination of a printing couple, a reciprocating bed provided with cutting or scoring devices for cutting or scoring a sheet after printing, a power shaft, a shaft driven therefrom, connections on the driven shaft for continuously operating the printing mechanism, connections from the driven shaft for reciprocating the bed, and a clutch for throwing the bed reciprocating connections into and out of operation. 75

8. In a printing machine, the combination of a printing couple, a reciprocating bed provided with cutting or scoring devices for cutting or scoring a sheet after printing, a power driven shaft, gears loose on the driven shaft, connections between the power shaft and the gears for effecting a continuous drive of the printing couple, connections between the driven shaft and the bed, and a clutch for throwing said connections 90 into and out of operation.

9. In a printing machine, the combination of a printing couple, a delivery cylinder to which sheets are delivered after printing, a reciprocating bed provided with cutting or scoring devices coöperating with the delivery cylinder to cut or score a sheet carried thereby, a common means for driving the printing couple, the delivery cylinder and the bed, and means for effecting a 100 silencing of the bed without affecting the operation of the printing couple and the delivery cylinder. 105

10. In a printing machine, the combination of a printing couple, a reciprocating support, cutting or scoring devices carried on the support for cutting or scoring a sheet after printing, a coöperating abutment, means for driving the couple and for effecting a relative movement between the support and the abutment, and means for silencing such movement without interrupting the driving of the printing couple. 110

11. In a printing machine, the combination of a printing couple, a movable support, sheet cutting and scoring devices carried thereby, a delivery cylinder to which the sheets are delivered from the printing couple and which coöperates with the cutting and scoring devices carried by the support for effecting a cutting and scoring of the sheet after printing, and means for effecting a relative movement between the support and the cylinder. 115

12. In a printing machine, the combina- 120

130

- tion of a printing couple, a movable support, sheet cutting or scoring devices carried thereby, a delivery cylinder to which the sheets are delivered from the printing couple which coöperates with the cutting or scoring devices carried by the support for effecting a cutting and scoring of the sheet after printing, and means for moving the support relatively to the cylinder.
13. In a printing machine, the combination of a printing couple, a movable flat bed, sheet cutting and scoring devices carried thereby, a delivery mechanism above the bed to which the sheet is delivered from the printing couple coöperating with the bed to cut or score the sheets, means for driving the couple, means whereby the bed is driven from the printing couple driving mechanism, and connections for throwing the bed out of operation without interrupting the

operation of the printing couple driving mechanism.

14. In a printing machine, the combination of a printing couple, a movable flat bed, sheet cutting and scoring devices carried thereby, a delivery mechanism to which the sheets are forwarded from the printing mechanism acting as an abutment against which the scoring mechanism operates to score or cut the sheet after it is printed, means for driving the couple, means for driving the bed from the printing couple driving mechanism, and connections whereby the bed may be thrown out of operation without interrupting the operation of the printing couple driving mechanism or the delivery mechanism.

In testimony whereof, I have hereunto set my hand.

ANTHONY SOREN BUSK.
